UNITED STATES PATENT OFFICE

2,416,913

LINOLEUM KNIFE

Bruno Del Debbio and Walter Lister,
San Francisco, Calif.

Application September 27, 1945, Serial No. 618,813

1 Claim. (Cl. 30—152)

1

This invention relates to improvements in knives, and has particular reference to a knife for cutting and scoring linoleum.

The principal object of this invention is to provide a combined knife and scoring tool, wherein all of the usual procedures necessary for fitting linoleum may be accomplished with a single tool, in contradistinction to the employment of several tools, any one of which may become lost and would, therefore, delay the fitting of the linoleum until the lost tool could be found or a new one substituted.

A further object is to produce a device of this character which is economical to manufacture and one which is easy to use.

A further object is to provide a tool wherein the customary procedures now employed are exactly the same, thereby eliminating any necessity for the operator learning a new procedure.

Other objects and advantages will be apparent during the course of the following description.

In the accompanying drawings forming a part of this specification and in which like numerals are employed to designate like parts throughout the same,

Fig. 1 is a side elevation of our tool.

Fig. 2 is an end elevation taken from the right of the drawing.

Fig. 3 is a vertical cross-section of the knife as shown in Fig. 1.

Fig. 4 is a fragmentary cross-sectional view, showing the scoring operation when fitting a seam.

Fig. 5 is a fragmentary view showing the scoring operation when using the scribe, as, for instance, in fitting along the edge of a wall.

Fig. 6 is a fragmentary cross-sectional view on an enlarged scale showing the manner in which the scoring pin of the scribe actuates.

Fig. 7 is a cross-sectional view taken on the line 7—7 of Fig. 1 and on an enlarged scale.

Fig. 8 is a fragmentary side elevation showing the use of the ripping knife.

Fig. 9 is a similar view showing the use of the cutting or scoring knife.

In the laying of linoleum it is most important that the linoleum be cut so as to fit either the sides of the walls, or any abutting surfaces. It is also important that the meeting edges of two pieces of linoleum fit without any cracks being visible.

It is, therefore, essential that the tools used in cutting linoleum perform a very accurate cutting and fitting operation on the linoleum.

It has been customary to provide a plurality

2

of tools, each one of which performs a certain function, and in using such tools it is necessary for the operator to transport a cumbersome kit containing same. If any tool became lost, then it becomes difficult for the operator to complete the linoleum laying operation.

Then, too, if the tools do not cooperate with each other; as for instance, the scoring arrangement on one tool may be too broad for the cutting-knife of the other tool, resulting in an imperfect fit. With our tool, all parts are designed to correspond in size one with the other, resulting in a perfect performance.

In the accompanying drawings wherein for the 15 purpose of illustration is shown a preferred embodiment of our invention, the numeral 10 designates the handle of the tool. This handle is slotted, as shown at 11, and is also provided with a slideway 12, in which a scribe-bar slides. This 10 scribe-bar has a roller 14 and is held in adjustable position by a cam-lock 16.

By viewing Fig. 6, it will be noted that the bar 13 has a cam-slot 17, in which the end of a scribing-pin, 18, rides. The end of this pin is 25 held against the bottom of the slot 17 by a spring 19 confined in a bore 21 formed in the handle 10.

The point, 22, of the pin forms a scoring-point for use as shown in Fig. 5, which will be described later.

30 The seam-scribe, as shown in Fig. 4, consists of a pin 23, adjustably held in the handle 10 by a set-screw 24, the end of the pin extending beyond the flattened surface 26 of the handle and is adapted to enter a recess 27 formed in a scribing-plate 28, this scribe-plate having an offset nose 29, adapted to engage the edge of a piece of linoleum, as, for instance, that shown at "A."

The scribe-plate 27 is slideably held to the handle 10, through the medium of a slot and pin arrangement, the pin being designated by the 35 numeral 31.

40 Mounted in the slot 11 is a double-ended ripping-knife 32, which is held in the slot through the medium of a pin 33, having a threaded head 45 34, engaging threads formed in a bore formed in the handle 10. This arrangement permits pressure to be exerted by the end of the pin against the ripping-knife.

Also mounted in the slot 11 is a scoring-knife 50 36. This scoring-knife is held in adjustable position, as shown in full lines in Figs. 1 and 3, through the medium of a spring 36, mounted upon the pin 33.

When the scoring-knife 36 is in scoring position, as shown in dotted lines in Fig. 3, a fric-

tional contact is made with the end of a screw 37, which helps to hold the knife-blade 36 in working position.

It will, therefore, be seen that we have produced a device which will accomplish all of the objects above set forth.

It is to be understood that the form of our invention herewith shown and described is to be taken as a preferred example of the same and that various changes relative to the material, size, shape and arrangement of parts may be resorted to without departing from the spirit of the invention or the scope of the subjoined claim.

Having thus described our invention, we claim:

In a tool of the character described, a handle 15 having a slot formed longitudinally thereof, a pair of knives positioned in said slot and secured

by a single screw-pin, said pin abutting one of said knives and forming a pivot for the other of said knives.

BRUNO DEL DEBBIO.
